UNITED STATES PATENT OFFICE

158,026

PLASTIC FILM TABLE COVER

Michael Angelo Susi, New York, N. Y., assignor to Toscony Fabrics Inc., New York, N. Y., a corporation of New York

Application June 14, 1949, Serial No. 3,261

Term of patent 3½ years

(Cl. D92—26)

To all whom it may concern:

Be it known that I, Michael A. Susi, a citizen of the United States, residing in the city of New York, county of New York, and State of New York, have invented a new, original, and ornamental Design for a Plastic Film Table Cover, of which the following is a specification, reference being had to the accompanying drawing, forming a part thereof.

The figure of the drawing is a plan view of a plastic film table cover, showing my new design.

I claim:

The ornamental design for a plastic film table cover, as shown.

MICHAEL ANGELO SUSI.
